TIME METER WITH ALARM DEVICE

Raymond Beaumann, Les Bois, Switzerland, assignor to Ebauches S.A., Neuchatel Canton, Switzerland

Application January 27, 1959, Serial No. 54,342

Term of patent 14 years

(Cl. D52—1)

I claim:

The ornamental design for a time meter with alarm device, substantially as shown.
